UNITED STATES PATENT OFFICE.

PASQUALE DELLA MONICA, OF HARRISON, NEW YORK.

REENFORCING BREAST FOR GARDEN IMPLEMENTS.

Original application filed April 28, 1921, Serial No. 465,273. Divided and this application filed May 15, 1923. Serial No. 639,122.

To all whom it may concern:

Be it known that I, PASQUALE DELLA MONICA, a citizen of the United States, residing at Harrison, in the county of West-
5 chester and State of New York, have invented certain new and useful Improvements in Reenforcing Breasts for Garden Implements, of which the following is a specification.

10 This invention relates to hand implements of the spade or shovel type and more specifically to the provision of a reenforcing breast and an inclined foot receiving face, especially well adapted for use in connection
15 with garden implements such as are described and claimed in my prior Patent No. 1,458,987 issued June 19, 1923, of which the present application is a division.

20 The primary object of the invention is the provision of a novel means for facilitating the insertion of the blade or fork of the implement into the soil or other material which it is desired to handle.

25 Another object of the invention is to provide a novel reenforcing construction which will add strength and rigidity to the blade, permitting the implement to be used for heavy work without the liability of bending or breaking the blade.

30 A further object is to provide a novel reenforcing construction for carrying the blade of a spade or shovel, and which will permit the removal of the blade when the same becomes worn or unfit for use.

35 A still further object is to provide the upper edge of the blade of the implement with a relatively broad inclined foot receiving face, whereby the blade can be readily and easily inserted into the soil or other material being handled, and one which will prevent the shoes of the user from becoming worn or cut as is customary with the use of the spades or shovels now in common use.

40 A still further object of the invention is to provide a hand implement of the above character, which will be durable and efficient in use, one that will be simple and easy to manufacture, and one which can be placed upon the market at a reasonable cost.

45 With these and other objects in view, the invention consists in the novel construction, arrangement and formation of parts, as will be hereinafter more specifically described, claimed and illustrated in the accompany-

ing drawing, forming a part of this specification, in which drawing—

55 Figure 1 is a perspective view of a shovel constructed in accordance with my invention, showing the reenforcing breast attached to a curved or offset handle.

60 Figure 2 is a perspective view of a spade of the straight handle type constructed in accordance with my invention.

65 Figure 3 is a perspective view of a spade fork construction in accordance with my invention, showing the relatively broad inclined foot receiving face formed integral with the prongs of the fork, and

70 Figure 4 is a longitudinal side view of the curved or offset type, showing a portion of the blade and reenforcing breast in section, illustrating the means for securing the blade to the breast.

75 In the drawing, where similar characters designate corresponding parts throughout the several views, the letter A designates the soil working or material handling portion of the tool; B the handle therefor and C the reenforcing breast.

80 The handles for these implements are generally designated by the letter B, which may be of the ordinary wooden construction, or constructed as disclosed in my co-pending application. The handle B may be of the straight type as shown in Fig. 2, or may have a curved or offset portion 7 near its lower end as is clearly shown in Figures 1 and 3 of the drawing, and may be provided at its upper end with any suitable type of hand grip 8.

85 90 The soil working portion for these implements is designated generally by the letter A, and may be made in any desirable shape or size, to be used in connection with the reenforcing breast C which will be hereinafter more specifically described.

95 Referring now to the reenforcing breast C, it preferably comprises an elongated main body portion 10, having a handle receiving extension 11 formed on its outer face 12 intermediate its ends, and adapted to be carried by the lower portion 9 of the handle B. The opposite or inner face 13 of the main body portion 10 has flanges 14 and 15 extending therefrom, longitudinal with the main body portion, and forming a transversely extending slot or groove 16 for the reception of the upper edge of the blade A.

This blade A may be detachably secured in the slot 16 by means of a suitable fastening element, such as a rivet 17. Thus when the blade becomes worn, or unfit for use it may be removed and replaced by a new one. If so desired, the central portion of the flanges 14 and 15 may be provided with the downwardly extending portion 18 in order to further reinforce the central portion of the blade. The main body portion 10 preferably extends the full width of the blade A, and its upper or outer face 12 is formed relatively broad, defining a rearwardly inclined face, and being in a plane diagonally crosswise of the axis of the handle receiving extension 11. This relatively broad rearwardly inclined face forms a foot rest or step, in order to facilitate the insertion of the blade into the ground. The inclination of this face 12 is one of the novel features of the invention, as it has been found in actual practice the inclination of the face permits a direct thrust of the foot in order to insert the blade into the soil or other material being handled.

The blade A of the spade fork as shown in Figure 3 is constructed of a plurality of prongs 19 formed on the transversely extending main body portion 20 at its inner face 21. The upper or outer face 22 is also of relative broad formation and rearwardly inclined so as to form a broad foot rest or step, which is the same as or similar to the inclined foot rest 12 shown in Figures 1 and 2. The body portion 20 also is provided with a handle receiving extension 23 formed

on its outer face 22 intermediate its ends and adapted to be carried by the lower portion 9 of the handle B.

From the foregoing description it can be seen that an improved reinforcement breast for garden implements has been provided, which is simple in construction, which will add strength and rigidity to the implement, and permit the use thereof for heavy work without the liability of bending or breaking the blade.

Various changes in details may be made without departing from the spirit of the invention or scope of the claims; but,

I claim:

1. A garden implement comprising a blade, a head portion extending across the upper portion of the blade for the full width thereof and having its upper face inclined rearwardly and downwardly, a handle engaging element extending from the upper face of the head portion, and a handle connected with the handle engaging element.

2. As an article of manufacture, a reinforcing breast for garden implement blades comprising an elongated main body portion of a length substantially the width of the blade, a handle receiving portion extending from the upper face of the body intermediate its ends and integral therewith, and spaced flanges extending from the under face of the body longitudinally thereof and providing a slot for receiving the upper end of the implement.

PASQUALE DELLA MONICA.
